PINKING MECHANISM FOR SEWING MACHINES

Adolph Spielman, Philadelphia, Pa., assignor to
Sarah Spielman, Philadelphia, Pa.

Application June 15, 1936, Serial No. 85,418

14 Claims. (Cl. 112—124)

This invention relates to pinking mechanism for sewing machines.

The object of the present invention is to provide pinking mechanism which can be applied to a standard make sewing machine, such, for example, as a "Singer" machine, without necessitating any changes in the mechanism of the standard sewing machine except the substitution of a few parts and the possible drilling and tapping of one or two holes in the frame of the standard sewing machine for securing the elements of the present invention thereto for co-operation with the standard operating parts of the standard sewing machine.

Another object of the invention is to provide a pinking attachment or pinking mechanism for a standard sewing machine which will lie in the greater part below the work plate or bed of the standard sewing machine and with a few parts above the work plate which may be readily removed in order that the standard sewing machine may be used for plain sewing or other work for which the machine was originally intended.

Another object of the invention is to produce an extremely simple form of pinking attachment for a standard sewing machine and to connect the primary operating element of the attachment to a normally movable element of that part of the mechanism of the sewing machine, i. e. the feeding mechanism, by which the length of stitch produced by the sewing machine is effected and whereby the operation of the pinking attachment will be in synchronization with the operation of the feeding mechanism of the sewing machine at all times and will vary with any variations that may be made in the stitch length, as provided for by normal adjustment of the feed-regulating mechanism of the sewing machine.

Specifically the object of the invention is to provide a rotary pinking wheel below the work-supporting surface of the sewing machine and a co-operating rotary anvil above the work-supporting surface of the sewing machine for co-operation with the pinking wheel; and to connect the driving mechanism of the pinking wheel with the rock shaft of the sewing machine by which the feed of the material along the work-supporting surface of the sewing machine is accomplished.

The construction and operation of the mechanism forming the subject matter of the present invention and such of the mechanism of the standard sewing machine as will be necessary to provide a clear understanding of the present invention will be fully disclosed hereinafter, refer-

ence being had to the accompanying drawings, of which:

Fig. 1 is a front elevation of a standard sewing machine illustrating the mechanism of the present invention as applied thereto;

Fig. 2 is an inverted plan view of the machine shown in Fig. 1;

Fig. 3 is a transverse sectional elevation taken on the line 3—3, Fig. 1;

Fig. 4 is a transverse sectional elevation taken on the line 4—4, Fig. 2;

Fig. 5 is a transverse sectional elevation substantially on the line 5—5, Fig. 2;

Fig. 6 is a fragmentary plan view partly in section as taken on the line 6—6, Fig. 1;

Fig. 7 is a longitudinal sectional elevation taken on the line 7—7, Fig. 6;

Fig. 8 is a view similar to Fig. 7 showing some of the elements in outside view and illustrating the mechanism as operating on material being stitched by the sewing machine;

Fig. 9 is a longitudinal sectional elevation taken on the line 9—9, Fig. 6;

Fig. 10 is a view similar to Fig. 6 showing a modified arrangement of the elements thereof;

Fig. 11 is a transverse sectional elevation taken on the line 11—11, Fig. 10;

Fig. 12 is a transverse sectional elevation taken on the line 12—12, Fig. 10;

Fig. 13 is a perspective view of certain of the elements shown in Fig. 12 in the course of operating upon material being fed across the work-supporting surface of the sewing machine;

Fig. 14 is a section on the line 14—14, Fig. 13;

Fig. 15 is a view similar to Fig. 7, and illustrating a modified arrangement of driving mechanism for the pinking wheel;

Fig. 16 is a transverse sectional elevation taken on the line 16—16, Fig. 15;

Fig. 17 is a sectional elevation taken on the line 17—17, Fig. 16;

Fig. 18 is a side elevation of a detail of the mechanism shown in Fig. 15;

Figs. 19 and 20 illustrate fabric swatches stitched together in the form of a so-called "French" seam and pinked in accordance with the principles of the present invention; and

Figs. 21 and 22 are similar views illustrating a flat seam and pinked edges as produced on the machine equipped with the mechanism forming the subject matter of the present invention.

As shown in Figs. 1, 2 and 3, the sewing machine includes a substantially flat bed plate or base 1 which is provided with depending feet or other downwardly extending lugs or projections

2, 3, 4, 5 and 6. The bed plate 1 is provided with the usual flat substantially horizontal work-supporting surface 7 above and to one end of which vertically projects the usual hollow standard 8 of the head 9 of the sewing machine. The head 9 also includes the usual laterally extending arm 10, at the outer end of which is the usual housing 11 which encloses and supports the upper portion of the needle bar 11 and presser bar 12 and the mechanism by which these bars are vertically reciprocated in timed relation to each other, the power for producing said vertical reciprocations of the bars 11 and 12 being provided through the usual main shaft 13 of the sewing machine to which power is applied from a suitable source through the usual grooved pulley 14.

The machine as usual is provided with a rotary bobbin, shuttle, or other stitch locking mechanism 15 which co-operates with the needle 16, carried by the needle bar 11, to produce the usual lock or chain stitch as commonly used in securing two or more plies of material together.

The stitch lock mechanism 15 as usual is rotated in the present instance continuously in one direction through a shaft 17 which is disposed under the bed plate 1 and which is provided, at the end opposite to that on which the stitch lock mechanism 15 is mounted, with a bevel gear 18.

30 The shuttle shaft 17, through the bevel gear 18, an intermeshing bevel gear 19 on the lower end of a vertical shaft 20, a bevelled gear 21 on the upper end of the shaft 20, and an intermeshing bevel gear 22 on the main shaft 13 of the machine, receives continuous rotation in one direction and at the same speed as the main shaft 13, whereby normal lock stitches are produced by co-operative action between the needle 16 and the shuttle mechanism 15.

40 In addition to the above, the normal standard sewing machine includes the usual feed dog 23 which co-operates with a presser foot 24 carried on the lower end of the presser bar 12 to feed the material being operated upon transversely of and from the front toward the back across the work-supporting surface 7.

The feed dog 23 includes the usual toothed face 25 which is raised into engagement with the under side of the fabric pressing the same upwardly against the under surface of the presser foot 24. The feed dog 23 then moves rearwardly to an extent corresponding to the length of the stitch desired, then downwardly, clear of the fabric, then forwardly in an opposite direction to that in which the fabric has been fed, and then upwardly into engagement with the under side of the fabric for a repeat of the feeding operation, these movements taking place after each stitch is made by co-operation between the needle 16 and the shuttle mechanism 15.

60 The feed dog 23, as usual, is carried on a more or less floating link 26, one end of which is pivotally connected at 27 to the upper end of a rocker arm 28, said rocker arm being rigidly connected to a rock shaft 29 which extends longitudinally of the bed plate 1 and is mounted for oscillation upon point bearings 30 and 31. The point bearings 30 and 31 are mounted in the depending lugs 3 and 5 respectively on the under side of the bed plate 1.

The opposite ends of the floating link 26 is slotted, as indicated at 32, for the reception of a guide pin 33 which is carried on the outer end of an arm 34. The arm 34 is rigidly secured to a 75 horizontal longitudinally extending rock shaft

35 which is disposed substantially parallel to the rock shaft 29 and is supported at its opposite ends by the usual point bearings 36 and 37 which are respectively mounted in the depending lugs 4 and 6 below the bed plate 1.

5 The rocking of the shaft 29 produces the longitudinal reciprocatory movement of the floating link 26, by which the material feeding and return motions of the feed dog 23 are produced; and the rocking of the shaft 35 produces the 10 vertical movements of the feed dog 23, by which said feed dog is caused to contact and release the fabric being operated upon.

The opposite ends of the two rock shafts 29 and 35 are respectively provided with arms 38 15 and 39. The outer end of the arm 39 on the rock shaft 35 is connected to one end of a reach rod or link 40, the opposite end of which is provided with an eccentric strap 41 which encircles an eccentric 42 which is secured to the main shaft 20 13 of the machine and by which, for each revolution of said shaft 13, the rock shaft 35 is oscillated and the feed dog 23 is raised and lowered, once for each stitch produced.

The outer end of the lever 38 on the rock shaft 25 29 is connected to one end of a link 43, the opposite end of which is provided with a yoke 44, parallel arms 45, 45 of which are slidably mounted in suitable grooves formed in the opposite sides respectively of a block 46 which encircles 30 a second eccentric 47 secured to the main shaft 13 and through which, for each revolution of said main shaft, the rock shaft 29 is oscillated and produces a backward and then a forward movement of the feed dog 23 for each stitch produced. 35

The length of the backward and forward movements of the feed dog 23 is regulated, and can be adjusted at will, through mechanism including a link 48 having one end pivotally connected to the yoke 44 of the link 43 and its opposite end connected at 50 to the outer end of one arm 51 of a stitch-regulating bell-crank lever 52, said bell-crank lever being pivoted at 53 to a fixed portion of the frame of the machine within the hollow standard 8. The second arm 54 of the 40 stitch-regulating bell-crank lever 52 is threaded at 55 for the reception of a clamp nut 56, the base of which is adapted to slide over a segmental surface 57 formed on the outer surface of the standard 8, when adjusting the machine 45 to produce a certain length stitch, and to be clamped firmly against said surface 57 when the desired stitch length is obtained.

The swinging of the bell-crank lever 52 about its pivot 53 regulates the length of the stitch produced by the machine and machines of this type are usually so built that the machine may produce from six to eighteen stitches per inch, for example, or any desired stitch length there-between.

60 The mechanism so far described constitutes the regular and standard parts of a standard sewing machine and which constitute no part of the present invention per se, such description being provided for the purpose of illustrating 65 how the mechanism constituting the subject matter of the present invention can be mounted on and actuated in definite relationship to the elements of a standard sewing machine.

The bed plate 1 of the standard sewing machine is normally provided with a recess extending inwardly from that end thereof above which the housing 11 is mounted, for the reception of a plurality of independent readily removable sections of a throat plate, which normally lie 70 75

flush with the work-supporting surface 1 of the bed plate 1 and which are normally removable for inspection and adjustment of the stitch mechanism of the machine. One of the throat sections is provided with a suitable slot in which the feed dog 23 operates and a suitable opening through which the needle of the machine passes for co-operation with the shuttle mechanism during the stitch formation. The present invention contemplates the substitution of a throat plate 60 in the inner end of the recess 59 for the corresponding throat plate section of the standard sewing machine.

Normally the shuttle shaft 17 is rotatably mounted in a bushing which in turn is fixedly mounted in an opening 61 formed in the depending foot or lug 2 of the sewing machine. The present invention contemplates the removal of such bushing and the substitution therefor of a sleeve shaft 62 which in addition to functioning as a bearing for the shaft 17 is utilized in the present instance to effect operation of the pinking wheel of the present invention as will be fully disclosed hereinafter.

The only further alterations necessary to the standard machine, in order to equip the same with the mechanism forming the subject matter of the present invention, is to drill and tap a hole 63 in the lug 2. The present mechanism otherwise utilizes such tapped openings as are already found in the standard sewing machine for securing the parts in place.

The present invention includes a rotary pinking wheel 65 which is mounted substantially in axial alignment with the shuttle shaft 17 and is provided with the cavity 66 within which the revolving shuttle mechanism 15 is disposed and by means of which the pinking face 67 of the wheel 65 is brought into relatively close relation to the needle 16.

The pinking face 67 is provided with cutting edges 68 which may be arranged in the usual zig-zag relation to each other or which may be in the form of curved undulations or of any desired shape to produce a pinked edge of any desired design.

The pinking wheel 65 is provided with a central bore 69 encircling the hub 70 of the rotary shuttle or bobbin or hook carrier 15 with sufficient clearance between the hub and the bore to permit the hub 70 to revolve freely within the bore without contact with the walls of the bore 69. In a like manner the cavity 66 is of such shape and such dimensions as to permit the rotary element 15 of the shuttle mechanism to revolve freely without contacting the walls of the cavity 66.

The pinking wheel 65 is also counterbored as at 71, the circular wall 72 of said counterbore functioning as one element of a clutch by which the pinking wheel is intermittently rotated, step by step, in accordance with and in synchronization with the cloth-feeding movements of the feed dog 23. A second element of the drive clutch for the pinking wheel is in the form of a disk 73 which is formed integral with or is suitably secured in a rigid manner to one end of the sleeve shaft 62 which surrounds and forms the bushing for the shuttle shaft 17.

As shown in Fig. 5, the disk 73 is provided with substantially triangular peripheral cavities 74 in which are mounted clutch rollers or balls 75, said elements being confined between the angular walls 76 and 77 of the cavities 74 and the inner circular peripheral face or wall 72 of the

counterbore 71 in the pinking wheel 65, springs 78 being seated in suitable pockets 79 formed in the substantially radial walls 77 of the cavities 74 and bearing against the rollers or balls 75 to maintain the rollers 75 in close bearing contact with the convergent walls 76 and 72 of the disk 73 and pinking wheel 65 respectively at all times, whereby rearward oscillatory movement of the sleeve shaft 62, i. e. movement in a counterclockwise direction, as viewed in Fig. 5, 10 will jam the rollers 75 between the disk 73 and the pinking wheel 65 and lock the two together and rotate the pinking wheel at the same time and to the same peripheral extent as the longitudinal rearward linear movement of the feed 15 dog 23, so that the pinking is effected step by step with the stitch formation of the sewing machine.

Oscillation of the sleeve shaft 62 in the opposite direction releases the disk 73 from the pinking wheel 65 permitting the pinking wheel to stand in the position to which it was moved at the extreme end of the first said oscillatory movement of the disk 73.

Corresponding forward movement of the pinking wheel is prevented by a roller 80 operating between the outer peripheral surface 81 of the pinking wheel 65 and an inclined surface 82 formed in a bracket 83 which is secured to the depending lug 2 of the bed plate 1.

Intimate contact between the roller 80, the peripheral surface 81 of the pinking wheel 65 and the inclined surface 82 of the bracket 83 is maintained by a spring 84 having one end bearing against the roller 80 and its opposite end secured to the bracket 83 by a screw 85.

The oscillations of the disk 73 are effected through an arm 86 which is rigidly secured to the end of the sleeve shaft 62 opposite to that on which the disk 73 is mounted. The lever 86 is 40 connected by a link 87 to a lever 88 which is rigidly secured to the rock shaft 29, that is, the shaft which produces the longitudinal reciprocations of the feed dog 23.

From the foregoing, it will be clear that as the 45 rock shaft 29 rocks in one direction to move the feed dog 23 backward, that is, in the direction in which the feed dog feeds the fabric away from the sewing needle 16, the disks 73 then locked to the pinking wheel 65 will, through the levers 86 50 and 88 and the connecting link 87, rotate the pinking wheel 65, at its peripheral pinking face 67, a distance equal to the linear movement of the feed dog 23, so that the pinking and sewing are effected equally step by step as the fabric is sewn 55 and fed away from the needle.

It will also be clear that any adjustment of the 60 stitch-regulating bell-crank 52 which affects the angle of oscillation of the rock shaft 29 and by which the feeding movements of the feed dog 23 65 are controlled will correspondingly affect the degree of rotation of the pinking wheel 65. Hence, regardless of the length of the stitch, that is, the extent of movement of the feed dog 23, lengthening or shortening the stitch will correspondingly affect the peripheral movement of the pinking wheel 65, so that a definite equal movement between the feed dog and the peripheral face 67 of the pinking wheel is at all times maintained.

In order to effect the pinking operation the 70 goods being sewn and pinked must be pressed firmly against the serrated peripheral edge or face 61 of the pinking wheel 65 and for this purpose a relatively thin flat anvil disk 90 is rotatably mounted directly above the peripheral edge of the 75

pinking wheel with the axis of the disc 90 disposed substantially at right angles to the axis of the pinking wheel 65 and with the serrated face 67 of the pinking wheel bearing against the under flat side 91 of the anvil disk 90 at one side of the axis thereof.

The anvil disk 90 is mounted for rotation about a stud 92, ball bearings 93 being provided to run in a grooved formed in the upper flat surface of 10 the anvil disk 90 and a groove 94 formed in the base 95 or undercut surface of a pressure arm 96, in which the anvil disk stud 92 is secured.

The pressure arm 96 is mounted immediately 15 above the upper surface 98 of the throat plate 60 which, in accordance with the principles of the present invention, is substituted for the back section of the normal throat plate of the machine. The throat plate 60 is provided with an anchorage 100 for the pressure arm 96 and by which longitudinal movement of the arm 96 is eliminated.

The anchorage 100 in the present instance comprises a pin 101 which is secured in the one 25 end of the pressure arm 96 opposite to that on which the anvil 90 is mounted, said pin 101 being disposed in a vertical slot 102 formed in a block 103 which is secured to the throat plate 60.

The actual pressure of the anvil disk 90 against the cutting face 67 of the pinking wheel 65 is effected by means of a screw stud 106 which is 30 secured in the throat plate 60 and on which is threaded a nut 104 seated in a counterbore 105 formed in the upper surface of the pressure arm 96. The throat plate 60 in turn is rigidly secured in place by screws 64 threaded into the regular 35 tapped openings in the base plate 1 by which the regular throat plate of the standard machine is secured in place.

Threaded into and through the pressure arm 96, adjacent the anchorage 100 therefor, is a 40 levelling screw 107, the lower end of which bears against the upper surface of the throat plate 60. A lock nut 108 is provided to secure the levelling screw 107 in the position to which it is adjusted.

In order to effect clean, sharp cutting of the 45 fabric between the serrated face 67 of the pinking wheel 65 and the flat surface 91 of the anvil 90 the surface 91 of the anvil must bear flatly against the serrated surface 67 of the pinking wheel and by manipulating the screws 104 and 50 107 such levelling of the anvil with respect to the pinking wheel may be readily accomplished, the screw 104 regulating the pressure of the anvil against the pinking wheel and the screw 107 functioning to effect the proper level of the anvil with 55 respect to the pinking wheel. The relatively loose anchorage 100 provided by the mechanism above described permits of such levelling movement of the arm 96, insofar as free vertical movement of the pins 101 is concerned.

60 In order to keep the pinking wheel from binding on the shuttle mechanism of the sewing machine as a result of the pressure required to effect cutting of the material between the serrated face 67 of the pinking wheel and the flat face 91 of the 65 anvil 90, the pinking wheel is supported independently of the shuttle mechanism and for that purpose the bracket 83 above referred to is formed of two parts 109 and 110 respectively.

The portion 109 of the bracket 83 is in the form 70 of a yoke, as clearly shown in Fig. 5, and it is in this part that the inclined surface 82 of a lock roller 80 of the pinking wheel 65 is formed, said inclined surface being formed in the upper end of one arm 111 of the yoke in such a manner that the axis of the roller 80 is at all times above the

axis of rotation of the pinking wheel 65. Approximately diametrically opposite to the roller 80, and preferably above the axis of rotation of the pinking wheel 65, and mounted in the second arm 112 of the yoke member 109, is a second roller 5 113 which revolves about an axle or pivot shaft 114. The rollers 113 and 80 contacting with the outer peripheral surface 81 of the pinking wheel 65 guide the pinking wheel horizontally in its rotation about the axis of the shaft 17, without 10 producing any lateral pressure in a horizontal plane against the shuttle shaft 17.

Below the pinking wheel 65 and bearing against the lower part of the peripheral surface 81 there is a pair of thrust bearings 115, 115, each of 15 which is rotatably mounted upon a stud 116. Each stud 116 is carried by an eccentric 117 which is rotatably mounted in the yoke 109, in order to adjust the thrust bearings 115 into contact with the peripheral surface 81 of the pinking wheel 65 in an accurate manner to take the downward thrust produced in the pinking operation without permitting the pinking wheel to exert any downward pressure on the shuttle shaft 17.

The thrust bearings 115 while they may be in the form of a plain wheel are preferably in the form of self-aligning ball bearings having the outer race thereof functioning as the rim of the bearing wheel and contacting with the peripheral surface 81 of the pinking wheel and the inner race mounted on the stud 116 with the balls of the bearing between said races in the usual manner to produce a substantially frictionless roller support for the pinking wheel.

The above construction throws the thrust of the cutting onto the yoke 109 which in turn, through a threaded pin 117 screwed into the threaded hole 63 formed in the depending lug or foot 2 of the machine, transfers the cutting 40 thrust directly to the solid rigid base of the machine.

In order to prevent wobbling of the pinking wheel as it rotates about the axis of the shuttle shaft 17, the throat plate 60 is provided with a 45 slot 119 through which the upper portion of the serrated face 67 of the pinking wheel extends. The walls of said slot bear against the opposite sides respectively of said wheel portion. The outer end face 120 of the pinking wheel is engaged throughout a substantial portion of the circumference of the pinking wheel, below the bed plate 1, by a rib having a bearing surface 121 and which is formed on the cover section 110 of the bracket 83, said cover plate section 110 being secured to 50 the yoke section 109 by a plurality of screws 122.

The remaining portion of the recess 59 in which the throat plate 60 is mounted is closed in the usual manner by a throat plate section 123 which may be the normal outer section of the 60 throat plate provided on a standard machine as shipped to a consumer.

The material to be seamed together or sewn 65 together and pinked while being sewed may be fed flatly to the needle, the feed dog, the pinking wheel and the anvil through the usual slot 125 formed between the under surface of the presser foot 24 and the upper surface of the throat plate with the two layers of the fabric *a* and *b* disposed in flat superimposed relation to each other as 70 illustrated in Fig. 21 and wherein the two layers of fabric will be secured together by a row of stitches *c* with a sufficient amount of material, indicated at *d* between the stitching *c* and the pinked edge *e* of each piece, said pieces of fabric 75

a and *b*, after sewing, being separated and spread out flatly as in Fig. 21 with the pinked portion *d* of each piece turned back upon the pieces *a* and *b* respectively to produce the ordinary common flat seam generally indicated at *f* in Fig. 22.

Preferably, the mechanism of the present invention is arranged to produce what is commonly known as a "French" seam indicated at *g* in Figs. 19 and 20 and to produce such a seam with a single row of stitches indicated at *c* in said figures, the two pieces of material *a* and *b* are fed to the needle and to the pinking mechanism through a suitable folding mechanism shown principally in Figs. 1, 6 and 9.

15 The folder includes an attaching plate 130 which is adjustably secured to the throat plate 60 by means of a screw 131 and to which is secured an inside folding plate 132 and an outside folding plate 133. The inside folding plate 20 132 extends upwardly from the attaching plate 130 and longitudinally thereof and beyond the end 137 of the plate 130, and provides a substantially flat support for the piece of material *b*. The plate 132 beyond the end 137 of the plate 130 25 bends downwardly and inwardly as indicated at 134 and 135 respectively and about which the sheet material *b* bends in a like manner.

Extending substantially parallel to the portion 30 135 of the inside folding plate 132 is a fabric-separating plate 136 which lies between the material *b* and the material *a* which latter rests on the upper surface of the throat plate 60 and on the upper surface 7 of the bed plate 1 in front of and in back of the throat plate. 35 The separating plate 136 forms part of the outside folding plate 133 and extends outwardly from the end 137 of the plate 130 and bends upwardly and is spaced from the curved portion of the plate 132, as indicated at 138, and then 40 inwardly over and in spaced relation to the flat portion of the inside folding plate 132, as indicated in Fig. 9.

The ends of the plates 132 and 136 which lie adjacent to the end 137 of the plate 130 are secured together and to the end 137 of the plate 130 as by soldering, welding, or in any other suitable manner to form the plates 130, 132 and 133 into a rigid unit.

The inside and outside folding plates 132 and 50 133 converge toward each other as they approach the stitching point, as clearly shown in Fig. 6, said plates terminating in front of the pressure arm 96 and in that way forming a fold in the piece of material *b* which overlies the underlying 55 piece of material *a*.

As the two pieces of the material merge from the rear edge of the folder composed of the plates 130, 132 and 133 they pass into the slot 125 between the presser foot 24 and the throat plate 60 60 to be stitched together and pinked, in the manner illustrated in Fig. 8.

The main body portion of the piece *b* slides over the top pressure arm 96 and under a plate 99 which is secured to and projects laterally 65 from the presser foot 24 as indicated in Fig. 8, and the needle 16 at the same time passes through the double thickness of the piece *b* and the single thickness of the piece *a* stitching the two together while the single thicknesses of the piece *a* and 70 the piece *b*, beyond the line of stitching *c* formed by the needle 16, pass between the anvil 90 and the serrated face 67 of the pinking wheel 65, to be pinked in the manner indicated in Figs. 19 and 20, thereby forming the French seam with a 75 single row of stitches *c*.

Heretofore, French seams have been formed by sewing two pieces of material together in the manner indicated in Fig. 21, after which the sheet of material *b* is folded upon itself, around the single row of stitches *c*, after which the material is again fed through the sewing machine to produce a second row of stitches through the superposed layers of the fold of the piece *b* and the single thickness of the piece *a*, between the row of stitches *c* and the pinked edges *e* of said 10 pieces *a* and *b*. Hence the apparatus just described produces in a single operation a French seam which heretofore has required two separate and distinct sewing operations.

In the apparatus hereinbefore described the 15 sewing and the cutting of the material between the serrated face 67 of the pinking wheel 65 and the flat surface 91 of the anvil 90 were effected on a common line extending longitudinally of the machine and passing through the axis of the 20 needle and the axis of the pinking wheel and by so doing seams along inside curved edges of previously shaped pieces of material *a* and *b* or outside curves of the design to which said pieces were cut could be readily pined.

In producing straight seams solely, or seams or curves of large radius, it is preferred to pink the edges of the two pieces of material in rearwardly offset relation to the stitching point rather than in line with the stitching of the pieces together 30 and for this purpose the arrangement of the anvil with respect to the pinking wheel as shown in Figs. 10, 11 and 12 is preferably employed. As shown in said figures, the axis of the anvil, while still remaining in a plane radially to the axis of 35 the pinking wheel, is tilted rearwardly with respect to the vertical axis of the needle, and, as shown in Fig. 10, where the axis of the needle and the axis of the pinking wheel are in the same line *x*—*x*, the point of contact between the pinking wheel and the anvil, and which is indicated at *y*—*y*, is spaced rearwardly from the line *x*—*x*, so that, as shown in Fig. 13, the needle 16 first 40 stitches the two pieces of material together, at the line *x*—*x*, and the pinking occurs subsequently thereto at the line *y*—*y*.

Aside from the tilting of the anvil, and consequently the pressure arm 96 as shown in Figs. 10, 11 and 12, the mechanism is substantially the same as that previously disclosed with the exception of the anchorage for the pressure arm 96 and the folder for the material *b*.

In Fig. 10, the lateral pins 101 are eliminated and a guide pin 139 is substituted and which projects upwardly from the throat plate 60 into a slot 140 formed in the pressure arm 96a.

In some instances, the folder instead of being mounted on the throat plate 60, as, for example, in Fig. 6, may be carried solely by the presser foot 24a, as indicated in Figs. 10, 12, 13 and 14, wherein the folder plates 132a and 133a are formed of one piece or soldered or otherwise secured together and to the said presser foot.

In some instances, the clutch drive for the pinking wheel 65 may be replaced by a drive of the character indicated in Figs. 15 and 16, wherein the disk 73 on the one end of the sleeve shaft 62 is supplanted by a rocker plate 173 having a laterally extending arm 174 which support bearings 175 and 176 respectively.

Rotatably mounted in the bearings 175 and 176 is a screw shaft 177 which, between said bearings, is provided with a multiple pitch screw or worm 178. The worm 178 meshes with a worm wheel 179 formed on the pinking wheel 165.

One end of the worm shaft 177 is provided with a disk 180 having triangular recesses 181 in which are placed clutch rollers 182. The clutch rollers 182 work between the walls of the triangular recesses 181 and the inner peripheral face 183 of an annular extension 184 formed on the one end of the bearing 176.

In the above case, when the sleeve shaft 62a rocks in one direction the worm shaft 177 is 10 locked to the plate 173 so that it cannot revolve in the bearings 175 and 176 and consequently, being in intermeshing engagement with the worm wheel 179, rotates the pinking wheel 165 in the same manner as before described. At the end of 15 the rocking motion of the sleeve shaft 62a in said direction and at the beginning of the oscillation of the sleeve shaft 62a in the opposite direction the pinking wheel 165 is held against reverse movement with the sleeve shaft 62a by the detent roller 82 in the same manner as before described.

The return oscillation of the sleeve shaft 62a rocks the plate 173 in a direction opposite to that in which it had been previously rocked and bodily 25 carries the worm 178 around the worm wheel 179 and due to the fact that the worm wheel is rigidly connected to the pinking wheel and is held against rotation along with and by the pinking wheel the worm 178 is caused to rotate thereby 30 rotating the worm shaft 177 in such a direction that the rollers 182 run freely in front of the shoulders 185 of the disk 180 and freely sliding over the surface 183 of the fixed annular extension 184 of the bearing 176.

35 As soon as the direction of oscillation of the sleeve shaft 62a is again reversed the detent roller 82 releases the pinking wheel and the rolls 182 become jammed between the annular surface 186 of the disk 180 and the inner peripheral surfaces 40 183 of the fixed annular extension 184, whereby the worm 178 is again locked against rotation and firmly locks the pinking wheel to the oscillating plate 173.

In order to provide the necessary room for the 45 swinging plate 173 and the bearings 175 and 176 as well as the worm 178 and worm wheel 179 the yoke support 109a which takes the downward cutting thrust of the pinking wheel is reduced in width and the mechanism noted above is positioned between said thrust plate 109a and the depending lug 2 of the machine.

In addition to the thrust pin 117, previously 55 described, which transferred the thrust of the plate 109 to the depending lug 2, the plate 109 is provided with a lug 190 at one of its sides and through which passes a screw 191 which secures the lug 190 to a pad 192 formed on the under side of the bed plate 1 and which is a part of the standard machine as sold to the consumer, said 60 pad having a suitably threaded opening for the reception of the screw 191.

In the instance of the structure shown in Figs. 15 and 16, wherein the width of the thrust plate 109a is reduced from that of the corresponding 65 plate 109 shown in Figs. 7 and 8, and in view of the elimination of the thrust pin 117 to provide the space for the worm 178 and its associated mechanism, the plate 109a as shown in Fig. 18 is provided with the lug 190 and screw 191 as 70 described above on the one side thereof and a corresponding lug 190a and screw 191a at the opposite side thereof and which is threaded into a suitable opening required to be made in the bed plate 1 of the machine and which would, together 75

with the lug 190 and screw 191 support the thrust plate 109a.

If and when it is desired to sew regular work, without pinking, the pressure arm 96 may be readily removed, carrying with it the anvil 90, 5 which together with the removal of the folding unit 130—132—133 places the machine in condition for such work. Also, if desired, the presser foot 24 with the guide plate thereon can be replaced by a regular presser foot without such 10 guide. The entire throat plate 60 may be removed and replaced by a throat plate having merely a slot or an upward bulge to accommodate or cover that portion of the pinking wheel which projects slightly above the plane of the work-supporting 15 surface 7, if desired, when the machine is to be used for regular sewing.

I claim:

1. A pinking attachment for a sewing machine having a work-supporting surface, said attachment comprising a rotary pinking wheel rotatably mounted beneath said surface about an axis substantially parallel to said surface and a cooperating rotary anvil disk rotatably mounted above said surface about an axis substantially 25 perpendicular to said pinking wheel axis with a flat side of the disk in contact with the peripheral face of the pinking wheel.

2. A pinking attachment for a sewing machine having a work-supporting surface, said attachment comprising a rotary pinking wheel rotatably mounted beneath said surface about an axis substantially parallel to said surface and a cooperating rotary anvil disk rotatably mounted above 30 said surface about an axis substantially perpendicular to said pinking wheel axis with a flat side of the disk in contact with the peripheral face of the pinking wheel, and means comprising a substantially flat bar disposed closely adjacent and substantially parallel to the plane of said surface 35 for supporting said anvil and exerting pressure by said flat side thereof against the peripheral face of the pinking wheel at the point of contact between the two.

3. A pinking attachment for a sewing machine 45 having a work-supporting surface, said attachment comprising a rotary pinking wheel rotatably mounted beneath said surface about an axis substantially parallel to said surface and a cooperating rotary anvil disk rotatably mounted above 50 said surface about an axis substantially perpendicular to said pinking wheel axis with a flat side of the disk in contact with the peripheral face of the pinking wheel, and means for varying the relation of one of said axes with respect to the 55 other of said axes to effect a flat contact of the flat face of the anvil across the peripheral face of the pinking wheel.

4. A pinking attachment for a sewing machine 60 having a work-supporting surface, said attachment comprising a rotary pinking wheel rotatably mounted beneath said surface about an axis substantially parallel to said surface and a cooperating rotary anvil disk rotatably mounted above 65 said surface about an axis substantially perpendicular to said pinking wheel axis with a flat side of the disk in contact with the peripheral face of the pinking wheel, means comprising a substantially flat bar disposed closely adjacent and substantially parallel to the plane of said surface 70 for supporting said anvil and exerting pressure by said flat side thereof against the peripheral face of the pinking wheel at the point of contact between the two, and means for varying the relation of one of said axes with respect to 75

the other of said axes to effect a flat contact of the flat face of the anvil across the peripheral face of the pinking wheel.

5. A pinking attachment for a sewing machine having a work-supporting surface, said attachment comprising a rotary pinking wheel rotatably mounted beneath said surface about an axis substantially parallel to said surface and a co-operating rotary anvil disk rotatably mounted 10 above said surface about an axis substantially perpendicular to said pinking wheel axis with a flat side of the disk in contact with the peripheral face of the pinking wheel, a low substantially flat element disposed above and lying closely 15 adjacent and substantially parallel to said surface and which rotatably supports said anvil disk, and means for applying pressure to said element to effect cutting pressure between said disk and said pinking wheel.

20 6. A pinking attachment for a sewing machine having a work-supporting surface, said attachment comprising a rotary pinking wheel rotatably mounted beneath said surface about an axis substantially parallel to said surface and a co-operating rotary anvil disk rotatably mounted 25 above said surface about an axis substantially perpendicular to said pinking wheel axis with a flat side of the disk in contact with the peripheral face of the pinking wheel, a low substantially flat element disposed above and lying closely 30 adjacent and substantially parallel to said surface and which rotatably supports said anvil disk, and means for actuating said element to bring the flat face of the disk into flat contact 35 across the peripheral face of said wheel.

7. A pinking attachment for a sewing machine which includes a work-supporting surface, means for feeding material along said surface, and means for intermittently actuating said feeding 40 means, said attachment comprising a rotary pinking wheel rotatably mounted beneath said surface about an axis substantially parallel to said surface, a co-operating anvil rotatably mounted above said surface about an axis substantially 45 perpendicular to said pinking wheel axis, and means operatively connected to the means for intermittently actuating said feeding means for intermittently actuating said pinking wheel in synchronization with said feeding means.

50 8. A pinking attachment for a sewing machine which includes a work-supporting surface, a vertically reciprocating needle, a rotary stitch locking mechanism beneath said surface and co-operating with said needle, means for feeding material along said surface, and means for intermittently actuating said feeding means, said attachment comprising a rotary pinking wheel rotatably mounted beneath said surface substantially 55 coaxially with said rotary stitch lock mechanism about substantially coinciding axes disposed substantially parallel to said surface with the pinking wheel disposed adjacent one side of said needle, a co-operating anvil comprising a disk rotatably mounted above said surface about an axis substantially 60 perpendicular to said coinciding axes with a flat side of said disk in contact with the peripheral face of the pinking wheel, and means operatively connected to the means for intermittently actuating said feeding 65 means for intermittently actuating said pinking wheel in synchronization with said feeding means.

70 9. A pinking attachment for a sewing machine which includes a work-supporting surface, a vertically reciprocating needle, a rotary stitch lock-

ing mechanism beneath said surface and co-operating with said needle, means for feeding material along said surface, and means for intermittently actuating said feeding means, said attachment comprising a rotary 5 pinking wheel rotatably mounted beneath said surface substantially coaxially with said rotary stitch lock mechanism about substantially coinciding axes disposed substantially parallel to said surface with the pinking wheel disposed adjacent one side of said needle, a co-operating anvil comprising a disk rotatably mounted above said surface about an axis substantially perpendicular to said coinciding axes with a flat side of said disk in contact with the peripheral face of the 10 pinking wheel, means operatively connected to the means for intermittently actuating said feeding means for intermittently actuating said pinking wheel in synchronization with said feeding means, and means for supporting said pinking 15 wheel independently of said axially aligned rotary stitch lock mechanism.

10. A pinking attachment for a sewing machine which includes a work-supporting surface, a vertically reciprocating needle, a rotary stitch 20 locking mechanism beneath said surface and co-operating with said needle, means for feeding material along said surface, and means for intermittently actuating said feeding means, said attachment comprising a rotary pinking wheel 25 rotatably mounted beneath said surface substantially coaxially with said rotary stitch lock mechanism about substantially coinciding axes disposed substantially parallel to said surface with the pinking wheel disposed adjacent one side of said 30 needle, a co-operating anvil comprising a disk rotatably mounted above said surface about an axis substantially perpendicular to said coinciding axes with a flat side of said disk in contact with the peripheral face of the pinking wheel, 35 means operatively connected to the means for intermittently actuating said feeding means for intermittently actuating said pinking wheel in synchronization with said feeding means, means for supporting said pinking wheel independently 40 of said axially aligned rotary stitch lock mechanism including a thrust bracket, and a plurality of thrust bearings carried by said bracket and engaging a peripheral surface of said wheel at relatively spaced points circumferentially thereof. 45

11. A sewing machine comprising a work-supporting surface, means for feeding two-ply material in superposed relation to each other along said surface, a stitching needle reciprocable perpendicular to said surface, a rotary stitch lock 55 mechanism co-operating with said needle to stitch said two-ply material together on said surface, a rotary pinking wheel substantially coaxially aligned with said stitch lock mechanism about substantially coinciding axes disposed substantially 60 parallel to said surface with the pinking wheel disposed below said surface and projecting slightly above said surface and a co-operating anvil comprising a disk rotatably mounted above said surface about an axis substantially 65 perpendicular to said coinciding axes with a flat side of said disk in contact with the peripheral face of the pinking wheel for pinking said two-ply material in spaced relation to said stitching, means for intermittently actuating said 70 feeding means and said pinking wheel synchronously to advance said material step by step and to pink said material as it passes along said surface, means for folding the upper ply of said material laterally upon itself and in advance of 75

said stitching and pinking to provide a doubling of said upper ply of material at said stitching mechanism, to produce a pinked French seam with a single row of stitches passing through said 5 three-ply material.

12. An attachment for a sewing machine having a work-supporting surface and adapted normally for sewing regular plain seams, said attachment comprising a rotary pinking wheel and 10 means for driving the same disposed below said surface and a co-operating rotary anvil disk above said surface in a plane substantially parallel to the plane of said surface for the production of plain pinked seams, and readily removable means 15 for supporting said anvil to permit production of regular plain or plain pinked seams at will.

13. An attachment for a sewing machine having a work-supporting surface and adapted normally for sewing regular plain seams, said attachment comprising a rotary pinking wheel disposed below said surface about an axis substantially parallel to said surface and a co-operating anvil rotatably mounted above said surface about 20 an axis substantially perpendicular to said pink-

ing wheel axis for the production of plain pinked seams, means above said surface and independent of said anvil for folding material prior to sewing and pinking to provide French pinked seams, and readily removable means for supporting 5 said anvil and separate readily removable means for supporting said folding means to provide for the production of regular plain seams, plain pinked seams, or French pinked seams at will.

14. A pinking attachment for a sewing machine having a work-supporting surface and a vertically reciprocating needle, said attachment comprising a rotary pinking wheel mounted below said surface with the axis thereof substantially parallel 15 to said surface in a vertical plane coincident with the axis of the needle, and a co-operating anvil rotatably mounted above said surface about an axis substantially perpendicular to said pinking wheel axis and at an angle to said vertical plane 20 with a flat side of said rotary anvil contacting with the peripheral surface of said pinking wheel at a point to one side of said vertical plane.

ADOLPH SPIELMAN.
